(57) **CLAIM**

The ornamental design for a tablet case, as shown and described.

DESCRIPTION

FIG. 1 is an isometric front view of a tablet case showing the new design;

FIG. 2 is a front view of the design of FIG. 1;

FIG. 3 is a back side view of the design of FIG. 1;

FIG. 4 is a right side view of the design of FIG. 1;

FIG. 5 is a left view of the design of FIG. 1;

FIG. 6 is a top view of the design of FIG. 1;

FIG. 7 is a bottom view of the design of FIG. 1;

FIG. 8 is an isometric back view of the design of FIG. 1; and, FIG. 9 is an isometric front view of the design of FIG. 1 showing a tablet as additional environment.

The broken lines immediately adjacent the shaded surfaces represent boundaries of the claimed design. All other broken lines depict unclaimed environment. The broken lines and unshaded regions bounded by the broken lines form no part of the claimed design.
